UNITED STATES PATENT OFFICE

ERNEST E. EMONS, OF WILMINGTON, DELAWARE, ASSIGNOR TO THE FUL-VUE SALES COMPANY, OF WASHINGTON, DISTRICT OF COLUMBIA, A FIRM

DESIGN FOR SPECTACLES

Application filed July 6, 1931. Serial No. 40,418. Term of patent 14 years.

To all whom it may concern:

Be it known that I, ERNEST E. EMONS, a citizen of the United States, residing at Wilmington, in the county of New Castle and State of Delaware, have invented a new, original, and ornamental Design for Spectacles, of which the following is a specification, reference being had to the accompanying drawing, forming a part hereof.

The figure is a front elevation of a spectacle, showing my new design.

I claim:

The ornamental design for spectacles, as shown.

ERNEST E. EMONS.
